TUNING ARRANGEMENT FOR SIGNALING SYSTEMS

Edward W. Forstrom, Stratford, Conn., assignor
to General Electric Company, a corporation of
New York

Application June 22, 1939, Serial No. 280,565

4 Claims. (CL 74—10)

My invention relates to an improved mechanism for tuning a signaling system and more particularly to an arrangement and apparatus for tuning a signaling apparatus to a selected one of a number of predetermined operating frequencies.

An object of my invention is to provide an improved and simplified tuning control arrangement which greatly facilitates the rapid and accurate tuning of signaling systems to any one of a number of predetermined operating frequencies.

A further object of my invention is to provide a tuning control arrangement which is equally adaptable for use with push button tuning control systems, either of the type having small pre-tuned condensers or inductances which may be switched into or out of a tuned circuit of the system or, on the other hand, of the type in which one or more of the main tuning condensers of the system are rotated by a mechanical arrangement to a selected one of a number of predetermined settings.

An additional object of my invention is to provide a tuning control of the aforementioned type wherein each tuning operation is accomplished by a series of mechanical movements constituting a tuning cycle, and my invention contemplates that the act of a person in actuating a suitable control to initiate a tuning cycle is accompanied by an automatic completion of the tuning cycle regardless of any subsequent and immediate actuation of one or more additional controls to initiate other tuning cycles.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which Figure 1 illustrates an embodiment of my invention, and Figure 2 illustrates a modification thereof.

Referring more particularly to Figure 1 of the drawings, there is shown in the upper left-hand corner of this figure a tuning condenser 10 whose adjustment determines the operating frequency of the signaling system, not shown, with which the condenser is used. The tuning condenser is comprised by a number of fixed plates 11 and a number of movable plates 12, the latter being secured to a framework 13, 14 and 15 for rotational movement about an axis 16 into and out of mesh with the fixed plates 11. It will be understood that while only one condenser 10 is shown,

the framework 13, 14 and 15 may support the movable plates of similar condensers where it is desirable that such condenser be arranged for uni-control operation with the condenser 10.

5 The signaling system may be tuned to any desired operating frequency within a continuous frequency band by angular movement of the movable condenser plates 12. This may be effected through one of the shafts 17, 18, provided on the 10 respective members 14, 15, from a suitable tuning control, not shown. The signaling system is tuned to any one of a number of predetermined operating frequencies, here shown by way of example as two in number, by a control arrangement 15 now to be described.

Positioned between the end plates 14, 15 is a channel-shaped rocker member 19. This member is arranged to be engaged in a manner presently to be described by a selected one of a pair 20 of tappets 20, 21 which are supported for reciprocatory motion on respective supports 22, 23. The supporting members 22, 23 are guided for reciprocal motion transverse to the axis 16 of the shafts 17, 18 by a framework, fragments of which 25 are shown at 27, 28 and 29. Each of the supports 22, 23 is normally biased to the extreme right-hand end of its travel by a helical spring 30.

Each of the supports 22, 23 has integrally formed projections 24 and 25 apertured for an 30 adjusting screw 26. The aperture in the projection 24 is internally threaded for threaded engagement with the left-hand end of the screw 26.

A pin 31 secures the tappet 20 in place on the support 22 while allowing the tappet to rotate about the axis of the pin to a selected position of adjustment. The tappet is locked in adjusted position by the provision of a clamping member 32 whose upturned end 33 is engaged by the end of the screw 26 as the latter is screwed 40 through the threaded aperture provided in the projection 24. The pin 31 is so arranged that its axis coincides with the axis 16 of the shafts 17 and 18 when the support 22 is moved to its extreme left-hand position to engage a selected tappet 45 with the rocker member 19.

The pretuning operation in which the position of each tappet 20 is adjusted to an angular position at which the signaling system is tuned to predetermined operating frequencies will now be explained by assuming that the support 22 and therewith the tappet 20 is moved to the left-hand end of its travel where the tappet 20 engages the top and bottom portions of the rocker member 19. The rocker member 19, of course, rotates 50 to a position determined by the angular position

of the tappet 20. The screw 26 may now be backed away from the upturned end 33 of the member 32 to allow the tappet 20 freely to rotate about the pin 31 and the signaling system may be tuned to a predetermined operating frequency by motion transmitted to the movable plates 12 of the condenser 10 through a suitable operating control, not shown, connected to one of the shafts 17, 18. Movement of the movable plates of the condenser causes a corresponding movement of the rocker member 19 and therewith a corresponding angular movement of the tappet 20 about the pin 31. When the signaling system has been tuned to the desired frequency, the left-hand end of the screw 26 is screwed into engagement with the upturned end 33 of the member 32 thereby to clamp the tappet 20 in its adjusted position of rotation about the pin 31. After each of the tappets 20 and 21 have been individually adjusted to an angular position corresponding to an operating frequency of the signaling system, any subsequent engagement of the tappet 20 or 21, with the rocker member 19 causes the tappet to move the rocker member 19, and therewith the movable plates 12 of the condenser 10, to a position corresponding to the respective operating frequency.

It is obvious that the signaling system may thus be tuned to a predetermined operating frequency merely by exerting a manual force on the right-hand end of a selected screw 26 to move one of the tappets 20, 21 into engagement with the rocker member 19. This, however, requires a certain amount of physical exertion, does not lend itself readily to remote control of the tuning operation, and does not completely insure that the operated tappet will always be moved to the extreme end of its travel where the rocker member 19 is accurately set at a position corresponding to the angular adjustment of the selected tappet.

To insure a more accurate and effortless control of the tuning operation, and one adaptable to remote control, an electric motor 34, shown in the lower left-hand side of Figure 1 is employed to drive a selected tappet to the extreme left-hand end of its travel. The motor is connected by gears 35 to a cam 36 whose cam surface 37 defines at least one tuning cycle. By a tuning cycle is meant that series of movements whereby a selected tappet 20 or 21 is moved from its position of rest (the position of the tappet shown in Figure 1) to the extreme left-hand end of its travel and is thereafter returned to its position of rest, this series of movements causing the tuning condenser 10 to be adjusted to that preselected position where the signaling system is tuned to a predetermined operating frequency. The cam 36 illustrated in Figure 1 has a cam surface 37 such that one complete rotation of the cam defines a tuning cycle.

The lower end of a cam follower 38 engages the cam surface 37 of the cam and is connected at its upper end to a plate 39 which is supported for rotational movement by stub shafts 40, 41. A helical spring 42 normally maintains the plate 39 in the position shown in Figure 1. Upon excitation of the motor 34 through a control circuit presently to be described, the cam 36 is rotated through the gearing 35 whereupon the cam follower 38 drives the upper edge of the plate 39 with a reciprocatory motion.

In order that the motion of the plate 39 may be transmitted to a selected one of the tappets 20, 21, a link member 43 is provided for each of the tappets. Each link member is guided for re-

ciprocal motion by a guiding slot 44 provided in the frame member 29 and a similar slot 45 provided in an additional frame member 46. The left-hand end of the link member 43 is arranged 5 in abutting relation to the projection 25 of the support 22. The right-hand end of each link 43 has integrally formed thereon a flange 47 upon the bottom of which is positioned a spherically shaped bearing member 48. A helical spring 49 is 10 positioned between the frame member 29 and the link member 43 and normally biases the latter about its contact with the upper edge of the slot 44 to cause the bearing member 48 to engage the upper surface of a frame member 50. The lower 15 edge of the left-hand end of the link member 43 is provided with a notch 51.

The driving connection between the plate 39 and one of the tappets 20, 21, is completed by the 20 operation of a selected manually actuatable push button 52 provided for each of the tappets. Each push button 52 is supported on the right-hand end of a lever 53 which is pivoted at 54 from the frame member 50. The left-hand curved end 55 of the lever 53 is moved by the operation of the 25 actuated push button into engagement with the underside of the flange 47 provided on the link member 43 and causes the link 43 to move about the point of its contact with the upper edge of the slot 45 provided in the frame member 48 thereby 30 to engage the upper edge of the plate 39 in the notch 51 of the link member.

After the push button 52 has moved sufficiently far to engage the plate 39 with the notch 51, an insulating pin 56 which is secured to the lever 53 35 engages the upper resilient arm 57 of a switch 58 to complete upon further depression of the push button an energizing circuit for the driving motor 34 through a pair of switch contacts 59. This energizing circuit may be traced from one side of 40 a source of power 60 through conductors 61, 62, the motor 34, the conductors 63, 64, 65, the switch contacts 59, and the conductors 66 and 67 to the other side of the power supply line.

The motor 34, when energized, drives the cam 36 45 through the gearing 35 in the direction indicated on the drawings by the arrow. The cam surface 37 moves the lower end of the cam follower 38 to the right. This motion is transmitted to the plate 39 and causes the upper edge of the plate 39 to move to the left. The upper edge of the plate is, however, in engaging relation with the notch 51 and thus causes a corresponding movement of the link member 43 to the left. In moving, 50 the link member 43 drives before it the support 22 and therewith a selected tappet 20, 21 corresponding to the particular key 52 which has been manually actuated. As the motor 34 continues to rotate, the tappet engages and moves the rocker member 19 about its axis until the latter reaches that angular position (determined by the preadjusted angular setting of the tappet) 55 where the condenser 10 tunes the signaling system to a preselected operating frequency. The plate 39, the link 43, the support 22, and the tappet having reached the leftward limit of their travel thereafter remain stationary and further movement of the cam 36 and cam follower 38 is 60 taken up by a lost motion connection between the cam follower and the plate 39. This lost motion connection is comprised by an angled projection 68 on the upper end of the cam follower which 65 engages an aperture 69 provided in the plate 39, by a guide pin 70 which loosely passes through 70 an aperture in the cam follower and is fixedly se-

cured to the plate 39, and by a helical spring 72 positioned on the guide pin 78 between the cam follower 38 and a nut 71 threaded on the right-hand end of the guide pin.

After the cam 36 has rotated through one-half of the tuning cycle defined by the contour of the cam surface 31, continued rotation of the cam allows the lower end of the cam follower 38 to move to the left under the biasing force of the helical springs 38, 42 and 72. As soon as the cam 36 has completed a tuning cycle and is again in the position shown in the drawings, the spring 48 causes the left-hand end of the link 43 to move upward thereby to move the notch 51 out of engagement with the upper edge of the plate 39.

In order that a tuning cycle may be completed after it has once been initiated, an insulating pin 73 is secured to the side of the cam 36 in a manner to engage the end of a flexible spring member 74, which carries the movable switch contact 75 of a switch 16. The switch additionally is provided with a fixed contact 77. These switch contacts are connected in the energizing circuit for the motor 34 in parallel with the switch contacts 59 of the switch 58. This parallel circuit includes a conductor 78 and the conductors 84, 85 and 86. It will be evident that upon sufficient rotation of the cam 36 to cause the pin 73 to move out of engagement with the resilient member 74, closing of the contacts 75 and 77 is effected whereupon the energizing circuit for the motor 34 is maintained closed even though the push button 62 may have been released subsequent to the initiation of the tuning cycle to open the switch contacts 59. The motor 34 thus continues to drive the cam 36 to the end of a tuning cycle at which time the pin 73 again engages the resilient member 74 to open the switch contacts 75 and 77.

In the event that the push button 62 is manually depressed for a period longer than that necessary to complete a tuning cycle, the motor 34 remains energized through the closed contacts 59 of the switch 58. To prevent repeated oscillatory movement of the link member 43 and tappet 20 (or 21) when this occurs, the right-hand end of the link member 43 in its movement to the left is arranged to slide over the curved end 88 of the lever 83 and abut against its outer periphery so that it is restrained against return movement as long as the push button 62 remains depressed. As the upper edge of the plate 39 thereafter moves to the right, the spring 48 raises the left-hand end of the link member 43 to disengage the upper edge of the plate 39 from the notch 51. Thus, any further reciprocal movement of the plate 39 is not thereafter transmitted by the link member 43 to the tappet and its support.

A signaling system having my invention embodied therein may be tuned to predetermined operating frequencies from points remotely situated from the signaling apparatus. This is accomplished by the provision of individual electromagnets 79 each positioned with its pole 80 under the center of a respective link member 43 (in the drawings, only one such electromagnet is shown for purposes of simplicity). The link member may itself be formed of magnetizable material or may support a magnetizable armature in position over the pole 80 of the electromagnet. In operation, the electromagnet and the motor 34 are energized from a remote point by closure of a remotely positioned switch 61. The energizing circuit for the electromagnet 79

may be traced from one side of the power supply line 60 through a conductor 81, a conductor 82, the winding of the electromagnet 79, a conductor 83, the contacts of the switch 61, and the conductors 85 and 87 to the other side of the power supply line 60. The energizing circuit for the motor 34 may be traced from one side of the power supply line 60 through the conductors 81 and 82, the motor 34, conductors 83 and 84, the contacts of the switch 61, and conductors 85 and 87 to the other side of the power supply line.

The energization of the electromagnet 79 in this manner causes the link member 43 to pivot about the bearing member 48 provided on its right-hand end thereby to engage the upper edge of the plate 39 in the notch 51. The motor 34 being simultaneously energized drives the plate 39 and therewith a selected tappet to move 20 the condenser 10 to a preselected position corresponding to a preselected operating frequency of the signaling system.

A modification of my invention is illustrated in Figure 2 wherein elements corresponding to like elements of Figure 1 are designated by like reference characters. This embodiment differs from Figure 1 in that the tuning condenser 10 of Figure 1 is replaced by a number of trimmer condensers 84, any one of which are switched, in a manner presently to be described into the tuned circuit of the signaling system to tune the system to predetermined operating frequencies. Figure 2 shows two such trimmer condensers enclosed within a single casing 95, one of the condensers having a pair of terminals 86 and 87 while the second has a pair of terminals 88 and 89. The capacity of the first condenser is adjusted by a small screw 90 while that of the second condenser is adjusted by a similar screw 91. The tuned circuit, not shown, of the signaling system into which the trimmer condensers are selectively switched terminates in the conductors 92 and 93. The conductor 92 is common to the terminals 86 and 88 of the trimmer condensers while the conductor 93 is common to a contact 94 and a contact 95, respectively, of a pair of switches 96 and 97. The switch 96 has a second contact 98 which is connected by a conductor 99 to the terminal 87 of the first trimmer condenser. The switch 97 likewise has a second contact 100 which is connected by a conductor 101 to the terminal 89 of the second condenser. Each of the switches includes a metallic bridging member 102 which is moved into or out of bridging engagement with the switch contacts by an actuating member 103. This latter member is constrained for reciprocal motion by suitable apertures provided in a frame member 104 and a frame member 105. To provide ease of assembly, the actuating member 103 is provided at its forward end with an aperture 106 into which projects a hooked end 107 of a second actuating member 108. The latter is constrained for longitudinal reciprocal motion by suitable slotted apertures provided in a pair of frame members 109 and 110. A helical spring 111 normally biases the actuating members 103 and 108 to a position where the bridging member 102 is out of bridging engagement with the switch contacts. Movement of a selected actuating member 108 to close switch contacts of a selected switch 96 or 97 is effected by the abutting engagement of the link members 43 against the turned-over end 112 of the individual actuating members 103. The remainder of the

actuating mechanism is as shown in Fig. 1, but is omitted from the present figure merely for purposes of simplifying the drawings.

It will be understood that the manual depression of a selected push-button 52 shown in Figure 1 causes a movement of a corresponding link member 43 and actuating members 103 and 108 to the right. This effects the closing of a selected switch 96 or 97 to connect into the tuned circuit of the signaling system one of the trimmer condensers 84. The operated switch is maintained closed, until like movement of another actuating member. To this end, notches 113 are formed in the lower edge of each actuating member 108, which are engaged by a movable latch 114, the latter being normally biased into engaging position with the notches by a helical spring 115. It will be understood that the movement of a selected actuating member 108 causes a downward movement of the latch bar 114 against the action of the spring 115 sufficient to release any actuating member 108 previously latched in switch-closing position.

In the claims which follow the general term "actuator" has been used to define that combination of elements which effects the tuning of a signaling system to preselected operating frequencies merely by the actuation of a particular element in the combination.

While I have shown particular embodiments of my invention, it will of course be understood that I do not wish to be limited thereto since many modifications may be made in the several elements and their arrangement, and I contemplate by the appended claims to cover all such modifications as fall within the true spirit and scope of my invention.

What I claim as new and desire to secure by Letters Patent of the United States is:

1. The combination, in a tuning system, of a plurality of parallel members arranged for reciprocation longitudinally thereof, each member being arranged upon reciprocation to tune said system to a corresponding frequency, an actuator common to all of said members and having motion when actuated in a direction longitudinal of said members, a motor to drive said actuator, a plurality of keys, each key corresponding to one of said members, and a plurality of longitudinally reciprocating rocker members each positioned between a respective key and a corresponding one of said parallel members and arranged when moved longitudinally to engage the corresponding one of said first members to actuate it to tune said system, each key being arranged upon operation thereof to rock its corresponding rocker member into engagement with said actuator and to energize said motor, whereby said motor operates said actuator and drives said rocker member longitudinally of itself to engage

one of said first members thereby to tune said system to a frequency corresponding to the actuated key.

2. The combination, in a tuning system, of a plurality of control members, each of said members being arranged upon longitudinal movement thereof to tune said system to a corresponding frequency, said control members being arranged in parallel, an actuator extending at right angles to all of said members and arranged to have movement longitudinally of said members, a plurality of connector members and keys, one key and connector member corresponding to each of said control members, each connector member being arranged to be actuated by its respective key into engagement with said actuator to be actuated thereby and when actuated drivingly to engage the respective control member to produce longitudinal movement thereof, a motor to drive said actuator, and means responsive to operation of any key to energize said motor.

3. The combination, in a mechanical tuning assembly for radio receivers, of a plurality of reciprocally movable elements, each of said elements corresponding to a predetermined frequency to which said receiver is tunable and arranged upon each reciprocation thereof to tune said receiver to the corresponding frequency, a motor driven cam and follower, said follower being arranged for oscillation by said cam, a plurality of keys, each key corresponding to one of said reciprocally movable elements, means actuated by said key mechanically to connect the corresponding reciprocally movable element to said follower for movement therewith, and to energize said motor, and means to maintain said motor energized during one oscillation of said follower and of the reciprocally movable element connected thereto by actuation of the key actuated.

4. The combination, in a mechanical tuning assembly for radio receivers, of a plurality of push rods arranged in parallel relation, each of said rods being arranged when actuated to tune said receiver to a corresponding frequency, a plurality of keys and a plurality of rocker members, each rocker member extending between a corresponding key and push rod for engagement therewith, a push member extending across all of said rocker members but normally disengaged therefrom, said rods, keys and members being so constructed and arranged that upon actuation of any key the corresponding rocker bar is rocked into driving engagement with said push member, and is driven thereby longitudinally of the corresponding push rod to operate said corresponding push rod to tune said receiver, and means responsive to actuation of any of said keys to actuate said push member to effect said tuning.

EDWARD W. FORSTROM.
